(57) **CLAIM**

The ornamental design for a work vehicle body, as shown and described.

DESCRIPTION

FIG. 1 is a top, rear, left perspective view of a work vehicle body showing our new design;

FIG. 2 is a left side elevational view thereof;

FIG. 3 is a right side elevational view thereof;

FIG. 4 is a top plan view thereof;

FIG. 5 is a rear end view thereof;

FIG. 6 is a front end view thereof;

FIG. 7 is a top, rear, left perspective view thereof shown with exemplary work vehicle environment;

FIG. 8 is a top, front, right perspective view of a work vehicle body showing another embodiment of our new design;

FIG. 9 is a right side elevational view thereof;

FIG. 10 is a left side elevational view thereof;

FIG. 11 is a top plan view thereof.

FIG. 12 is a front end view thereof;

FIG. 13 is a rear end view thereof; and,

FIG. 14 is a top, front, right perspective view thereof shown with exemplary work vehicle environment.

The broken line representations in the figures, including the broken line work vehicle environment shown in FIGS. 7 and 14, show unclaimed environment or boundaries, and thus form no part of the claimed design.

The nature of this product is a work vehicle, such as used in the construction and forestry industries.
